METHOD OF INCREASING OCTANE NUMBER
OF MOTOR FUELGeorge W. Ayers, Chicago, Ill., assignor to The
Pure Oil Company, Chicago, Ill., a corporation
of OhioNo Drawing. Application June 11, 1945,
Serial No. 598,925

9 Claims. (Cl. 260—683.5)

1

This invention relates to a method for increasing the octane value of gasoline and of hydrocarbons boiling within the gasoline range.

It is well-known that straight-chain paraffin hydrocarbons having 5 or more carbon atoms in the molecule have low anti-knock value and for that reason are objectionable in gasoline used for ignition type internal combustion engines. Various methods have been proposed for converting straight-chain paraffins to other types of hydrocarbons which have higher anti-knock value. One such method is to isomerize these hydrocarbons to branched-chain hydrocarbons using aluminum chloride and other isomerizing catalysts. The difficulty with the Friedel-Crafts and other isomerizing catalysts which are known for isomerizing straight-chain paraffins to iso-paraffins is that these catalysts are reactive with respect to unsaturated and aromatic hydrocarbons, causing loss of these constituents in the motor fuel. Furthermore, Friedel-Crafts type catalysts cause some cracking of the liquid hydrocarbons to gaseous hydrocarbons.

I have discovered that if straight-chain hydrocarbons or gasoline containing straight-chain hydrocarbons is allowed to stand in contact with certain metal cyanides for a sufficiently long period of time, isomerization of the straight-chain hydrocarbons to hydrocarbons having high octane value occurs, so that the overall octane number of the hydrocarbon or hydrocarbon mixture is higher than the material before treatment with the cyanide. The metal cyanides which are effective for improving the octane number of straight-chain paraffin hydrocarbons are potassium cyanide, cuprous cyanide, nickel cyanide, mercuric cyanide and silver cyanide. The aforesaid metal cyanides are effective in improving octane number of liquid hydrocarbon mixtures containing straight-chain paraffin hydrocarbons in the presence of unsaturated and aromatic hydrocarbons without affecting the latter, so that no loss in the gasoline boiling constituents occurs.

The treatment of the gasoline or gasoline-boiling hydrocarbons with the metal cyanide may be effected simply by permitting the gasoline to stand in contact with powdered, granular or lump cyanide for a period of time in excess of two days and preferably for a period of more than twenty days. A simple method for effecting contact is to place granular metal cyanide in liquid permeable containers in a vessel in which the gasoline is stored, or to place lump metal cyanide on one or more perforated trays in the vessel containing the gasoline. The cyanide is prefer-

ably placed above the bottom of the vessel in order to prevent any water which settles out of the gasoline from coming in contact with the cyanide and dissolving it. The cyanide is insoluble in the gasoline and can be used indefinitely.

Although the gasoline may be mixed or agitated in order to bring it into more intimate contact with cyanide and thereby reduce the time of contact, agitation is not necessary. The treatment is carried out at ordinary atmospheric temperatures and pressures and the effectiveness of these metal cyanides in increasing octane number does not appear to be affected by temperature or pressure. The treatment can be carried out at temperatures as low as -40° F. and as high as 500° F.

The amount of cyanide which is contacted with the gasoline or other hydrocarbon material may range from a trace to as much as 100% by weight or more of the gasoline.

The following examples will demonstrate the effectiveness of the metal cyanides in improving the octane number of gasoline or gasoline-boiling hydrocarbons:

Example I

600 cc. of gasoline comprising a blend of straight-run and high pressure, thermally cracked gasoline, containing olefinic and aromatic hydrocarbons, was allowed to stand for thirty-three days in a closed vessel containing 60 grams of granular potassium cyanide. No change in the potassium cyanide was noticeable at the end of this period. The gasoline was tested for octane number in accordance with standard A. S. T. M. method and was found to have an A. S. T. M. octane number of 59.6 before treatment and 60.8 after treatment.

Example II

600 cc. of the same gasoline used in Example I was allowed to stand in a closed vessel for thirty-three days with 60 grams of granular cuprous cyanide. No noticeable change in the cuprous cyanide occurred. The gasoline before treatment had an A. S. T. M. octane number of 59.6 and after the treatment had an octane number of 60.2.

Example III

500 cc. of n-heptane was allowed to stand in a closed vessel for thirty-three days with 20 grams of granular potassium cyanide. The potassium cyanide remained unchanged, but the A. S. T. M. octane number of the n-heptane was 2.3 after

the treatment as compared to an A. S. T. M. octane number of zero before treatment.

Example IV

500 cc. of n-heptane was allowed to stand in a closed vessel for thirty-three days with 20 grams of granular cuprous cyanide. No change in the cuprous cyanide occurred, but the n-heptane had an A. S. T. M. octane number of 2 after the treatment as compared to an A. S. T. M. octane number of zero before the treatment.

Example V

25 cc. of n-heptane was allowed to stand at room temperature in a closed vessel for forty-two days in contact with 3 cc. of a saturated aqueous potassium cyanide solution. At the end of this time the hydrocarbon material was analyzed by the modified Moldavskii method, described and claimed in application, Serial No. 474,748, and it was found to contain 4% of iso-paraffins. It will be seen, therefore, that the solution of the cyanide was also effective in causing isomerization.

The modified Moldavskii method differs from the conventional Moldavskii method, principally in that approximately 0.05 gram of dry uranyl nitrate is added to each 25 cc. of solution in connection with chlorination with antimony pentachloride and the solution is allowed to stand for at least six hours in a closed vessel at a temperature of 70-90° F. in order to complete the chlorination.

Although the increase in octane number is not large, it is significant and is obtained at substantially no expense other than the initial cost of the cyanide which may be used over and over again to treat new batches of gasoline. The treatment is applicable to gasoline either before or after the addition of tetraethyl lead and can be carried out at the refinery or during storage at any other point such as a bulk plant or service station.

It will be seen, therefore, that I have found a simple and inexpensive method for improving the knock reading of motor fuels without causing any loss of the motor fuel.

It is claimed:

1. The method of improving the anti-knock value of gasoline-boiling paraffinic hydrocarbons when used in ignition-type internal combustion engines comprising contacting said hydrocarbons for a period of at least two days with a metal cyanide insoluble in said hydrocarbons selected from the group consisting of potassium cyanide, cuprous cyanide, nickel cyanide, mercuric cyanide and silver cyanide and separating said hydrocarbons from the cyanide.
2. Method in accordance with claim 1 in which the cyanide is potassium cyanide.
3. Method in accordance with claim 1 in which the cyanide is cuprous cyanide.
4. Method in accordance with claim 1 in which the cyanide is nickel cyanide.
5. The method of improving the anti-knock value of gasoline-boiling hydrocarbons containing a substantial amount of straight chain paraffinic hydrocarbons when used in ignition-type internal combustion engines comprising contacting said hydrocarbons under existing atmospheric conditions with a metal cyanide insoluble in said hydrocarbons selected from the group consisting of potassium cyanide, cuprous cyanide, nickel cyanide, mercuric cyanide, and silver cyanide for a period of time not less than two days sufficient to effect an increase in octane number and separating the hydrocarbons from the cyanide.
6. Method in accordance with claim 5 in which the period of time is at least twenty days.
7. Method in accordance with claim 5 in which the metal cyanide is potassium cyanide.
8. Method in accordance with claim 5 in which the metal cyanide is cuprous cyanide.
9. Method in accordance with claim 5 in which the metal cyanide is nickel cyanide.
